UNITED STATES PATENT OFFICE.

JOHN ROY STARK, OF RACINE, WISCONSIN, ASSIGNOR TO WEBSTER ELECTRIC COMPANY, OF RACINE, WISCONSIN, A CORPORATION OF WISCONSIN.

IGNITION-MAGNETO.

1,342,607.

Specification of Letters Patent.

Patented June 8, 1920.

Application filed April 26, 1919. Serial No. 292,783.

To all whom it may concern:

Be it known that I, JOHN ROY STARK, a citizen of the United States, residing at Racine, in the county of Racine and State of Wisconsin, have invented a certain new and useful Improvement in Ignition-Magneto, (Case 7,) of which the following is a full, clear, concise, and exact description, reference being had to the accompanying drawings, forming a part of this specification.

My invention relates to ignition magnetos, and primarily has for its object the provision of a device of this class which is capable of developing a good "starting spark" and of developing good sparks at the lower engine speeds when the armature or rotor of the magneto is driven at a comparatively low rate of speed. Briefly, I accomplish these objects:

First: By the provision of means, which may be under the control of the engine operator, adapted, at the lower engine speeds, for instance when operating with retarded spark, to accelerate the relative motion between the armature or rotor and the pole faces with which it coöperates; and

Second: By the provision of novel means, which likewise may be under the control of the operator, for accelerating the operation of the primary circuit interrupter contacts.

Before proceeding to a detailed description of the ignition magneto of my invention, which will be best understood by reference to the accompanying drawings, I will point out that I have illustrated the improvements which characterize my present invention in connection with a magneto, which, in such of its parts as constitute no part of my present invention, may, if desired, be substantially like the ignition magneto disclosed in the co-pending application of Arthur C. Kleckner and Walter Brown, Serial No. 271,576, filed July 17, 1919. In the following description I will therefore make but brief reference to those features of the magneto machine with the details of which my present invention is not particularly concerned. It is to be understood, however, that the application of the improvements of my invention to a machine of the Kleckner & Brown type is merely representative, as the novel features of my invention are capable of application in a great many types of ignition magnetos.

In the accompanying drawings illustrating my invention:

Figure 1 is a view illustrating in axial section those parts of the ignition magneto with which my invention is concerned;

Fig. 2 is an end view taken on line 2-2 of Fig. 1 and looking in the direction indicated by the arrows, this view illustrating particularly the interrupter, its mounting, and means for its operation;

Fig. 3 is a fragmentary sectional view taken on the line 3-3 of Fig. 1, looking in the direction indicated by the arrows;

Fig. 4 is a vertical sectional view taken on the line 4-4 of Fig. 1, looking in the direction indicated by the arrows; and

Fig. 5 is a fragmentary vertical sectional view similar to Fig. 4 but showing certain of the parts in changed position.

Similar characters of reference refer to similar parts throughout the several views.

The drawings illustrate a magneto comprising the two-part housing 10, the lower part of which constitutes the machine frame, its removable end closure 10^a, magnets 11, 80 pole pieces 12 cast in the machine frame, transformer and condenser housing 13, and distributor devices indicated as a whole by the reference numeral 14. My invention is not concerned with the details of these elements of the machine. They may be of the Kleckner & Brown type, as illustrated, or they may be of any other desirable construction.

Mounted between the pole pieces 12 is 90 a cylindrical timing sleeve 15, comprising the magnetic segments 15^a—15^b, which, as is well known in the art, in effect constitute adjustable faces for the pole pieces 12, and the non-magnetic segments 15^b, 15^b. The 95 timing sleeve may, if desired, be of substantially the same construction as the one shown and described in the Kleckner & Brown application previously mentioned, but not necessarily so. Generally speaking, timing 100 sleeves of this type are well known in the art, and I contemplate applying the improvements to be hereafter mentioned to any suitable form of timing sleeve.

As is best shown in Fig. 1, the left-hand 105 end of the timing sleeve 15 is provided with a bearing 16 formed integral with, or carried by, the machine frame as shown, whereas the right-hand end of the timing sleeve, or more specifically, its end closure 17, is 110

mounted in a bearing 18 formed integral with or carried by the machine frame, as illustrated.

Mounted for rotation within the timing sleeve 15 is the armature 19. I have illustrated an armature substantially similar to that shown and described in the said Kleckner & Brown application, which armature comprises a plurality of substantially I-shaped laminations 20, constituting the armature core, provided with the generating winding 21, the said core and winding being supported in a non-magnetic armature frame comprising the non-magnetic segmental side pieces 22, 22 which bridge the spaces between the segmental ends of the I-shaped laminæ 20, and thus give the entire armature structure a true cylindrical shape. The details of the armature are, however, not particularly important, in so far as my invention is concerned.

The armature is provided with trunnions 23 and 24, the trunnion 23 being provided with a ball bearing 25 in the left-hand end 25 of the timing sleeve (Fig. 1), and the trunnion 24 being provided with a similar ball bearing 26 carried by the end closure 17 of the timing sleeve, the said trunnion 24 extending through the magnetic housing end 30 closure 10^a and being adapted to have the usual means for driving the armature attached thereto. It will be assumed that in the operation of the present machine the armature shaft is driven in what would be 35 the clockwise direction in Figs. 2 and 3, and the counter clockwise direction in Figs. 4 and 5.

In so far as the interrupter mechanism is concerned, my invention relates to the mounting and method of operating the interrupter contacts rather than to the particular way in which the circuit connections of the magneto are made. The fixed and movable interrupter contacts are illustrated 40 respectively at 27 and 28 in Fig. 2. The fixed contact is carried by a suitable screw 29, carried by a lug 30, formed integral with a brush holder 31, carried by, but insulated from, the left-hand end of the timing sleeve 45 15 (Fig. 1), the said brush holder provided with a suitable cylindrical brush 32 and its coöperating spring 33, which tends to hold the brush in contact with the insulated contact segment 34. The construction of the 50 parts just described is substantially similar to the corresponding parts shown in the Kleckner & Brown application before mentioned, and inasmuch as the present invention is not concerned with the magneto circuit connections, it will suffice to say that the surface of the segment 34 with which 55 brush 32 coöperates is of sufficient length to insure contact between the brush and the segment at any position to which the timing sleeve may be moved by the devices presently

to be described. It is to be understood that the segment 34 constitutes part of the insulated side of the primary circuit. The armature winding 21 has one end thereof grounded to the armature frame and timing sleeve 15, whereas the other end of the armature winding is insulated and connected with the insulated conductor 35, which extends through the armature trunnion 23, as illustrated in Fig. 1. The spring arm 36 70 carried by the terminal 37 bears against the exposed end of the insulated conductor 35, and a suitable insulated conductor indicated at 38 leads from the terminal 37 as a part of the insulated side of the primary circuit. 75 The several devices thus far described are particularly adapted to be used in connection with the specific circuit arrangement shown and described in the Kleckner & Brown application, but in so far as my present invention is concerned, the circuit connections intermediate the terminal 37 and the insulated interrupter contact are immaterial. Those of Kleckner & Brown may be employed, but that is not essential.

The grounded interrupter contact 28 is carried by the spring 39, forming a part of the contact arm 40, which is pivotally mounted upon, and electrically connected with, the adjacent end of the timing sleeve 95 15 at 41, the said contact arm provided with the plug 42 coöperating with the cam 43, carried by the armature trunnion 23. The operation of the coöperating interrupter contacts 27 and 28 effects the opening and 100 closing of the primary circuit in the usual manner. With the interrupter sleeve stationary and the interrupter cam 43 rotating in a clockwise direction (Fig. 2), the separation of the interrupter contacts would be 105 effected substantially like any ordinary primary circuit interrupter. However, as will presently be described in detail, I provide means arranged and adapted to move the timing sleeve, and consequently, the interrupter contacts and the parts by which they are carried, in a direction opposite to the direction of rotation of the cam 43, so that the separation of the contacts by the cam 43 is effected at a much higher rate of speed 110 than would be the case, were the relative motion between the cam 43 and its coöperating insulated contact arm plug 42 accomplished solely by the normal rotation of the cam 43.

The magneto frame may, if desired, be provided with a grounding brush 44, carried within the brush holder 45, and held in contact with the left-hand end of the armature frame (Fig. 1) by the spring 46, the grounding brush extending through an elongated slot 47 in the timing sleeve to permit engagement between the grounding brush 44 and the armature frame regardless of the position to which the timing sleeve may be 130

moved in the operation of the magneto. In so far as this description is concerned it will suffice to say that the brush 44 serves to insure electrical connection between the 5 grounded side of the armature winding, the magneto frame, and the timing sleeve, which, being mounted in the bearings in the magneto frame, is of course in electrical contact therewith.

10 Referring now more particularly to Figs. 1, 4 and 5, it will be noted that I have disposed around the timing sleeve 15 a ring 48, which is adjustably mounted in the bearing 49 integral with, or carried by, the machine 15 frame, as shown. Forming a part of the ring 48, and extending through a suitable slot 50 in the housing 10, is the timing lever 51, which in Figs. 4 and 5 is shown in its "retard" position. The "advance" position 20 of the timing lever is indicated by dotted lines in Fig. 5.

It will be noted that the ring 48, of which the timing lever 51 forms a part, is provided with a peripheral flange 52, carrying two 25 pins 53 and 54. A coiled spring 55, lying in a channel formed in the peripheral flange 56 forming a part of the timing sleeve 15, has one end thereof attached to the pin 53 and the other end thereof attached to a lug 30 57, which may be in the form of an enlarged portion of the flange 56 of the timing sleeve. The spring 55 is constantly under tension, and thus tends at all times to hold the lug 57 in engagement with the pin 54, as illustrated 35 in Fig. 4. It will thus be seen that by manipulating the timing lever 51, the timing sleeve may be given any desired adjustment with respect to the pole pieces 12, within the 40 limits of the movement of which the timing lever is capable.

The bearing 49 for the right-hand end of the timing sleeve (Fig. 1) is conveniently provided with a laterally extending portion 58, whereon is pivotally mounted one end of a lever 59, the other end of which is connected by a link 60 with the timing sleeve lug 57. Intermediate its ends the lever 59 is provided with a surface 61, arranged to be engaged, for the purpose presently to be explained, by the cam 62 of fiber, steel, or other suitable material keyed or otherwise fixed upon the armature trunnion 24. It will be noted that the timing sleeve is cut away, as indicated at 63, to accommodate the lever 61 and that the bottom of the machine housing is apertured at 64 to permit the free end of lever 61 to travel to its lowermost position.

Referring to Fig. 3, and, for the moment, disregarding the functions of the lever 59 and cam 62, it will be understood that in the operation of the armature the peak of the current wave generated in winding 21 is attained twice in each revolution, shortly after 65 the trailing edges of the armature core

laminæ 20 have left the magnetic pole face segments, 15^a, 15^a of the timing sleeve, the occurrence of the wave peak being advanced or retarded by the adjustment of the timing sleeve with respect to the pole pieces 12, 12. 70 The generation of the current as just described, and the functions attributed to the timing sleeve magnetic pole face segments 15^a, 15^a are well known in the art.

Heretofore great difficulty has been encountered in magneto ignition due to the fact that at starting and at the lower engine speeds, with the rotor of the magneto being slowly driven, the movement between the armature or rotor and its co-operating pole 80 faces has been too slow to create a satisfactory current in the generating winding. Likewise, due to the same reason—that is, the slow speed of the rotor at starting and at the lower engine speeds—the opening of 85 the interrupter contacts as a general rule has been slow, which of course has had a serious effect upon the ultimate spark. These difficulties are overcome by the arrangement herein described.

In the operation of my magneto, assuming the timing lever to be in the "retard" position shown in Fig. 4, the cam 62, acting through the lever 59, causes the timing sleeve to move in a direction opposite that of armature rotation at the time that the trailing edges of the armature core sectors are leaving the pole face segments of the timing sleeve. Thus, the relative movement between the armature and pole faces is materially accelerated, with a correspondingly more rapid change in the magnetic lines traversing the generating winding, and as a result the generation of a current of better 90 95 100 105 value in the generating winding of the armature.

Let us assume that in the operation of the magneto the armature and cam 62 have reached the positions illustrated in Fig. 5. In this view the armature is rotating in a counter clockwise direction, and its trailing edges are about to leave the magnetic pole face segments of the timing sleeve. At this instant the cam 62, acting against lever 59, serves to move the timing sleeve, and consequently the pole face segments, which are a part of the sleeve, in a direction opposite that of armature rotation and against the tension of spring 55. Thus the separation of the trailing edges of the armature and 110 115 120 125 130 the pole face segments of the timing sleeve is accelerated. This operation is repeated as the armature continues to rotate, the cam 62 moving the timing sleeve in a direction opposite that of armature rotation twice for every revolution of the armature, the spring 55 tending at all times to hold the lever 59 in engagement with the cam 62.

It will be understood that in the use of my magneto the timing lever will be held 130

in the "retard" position at starting and whenever, at the lower engine speeds, it is desired that the cam and lever mechanism just described shall function. When the 5 timing lever is moved to the "advance" position indicated by dotted lines in Fig. 5, the lever 59 is held in such position that the cam 62 cannot act thereon to move the timing sleeve, as previously explained. Furthermore, with the timing lever in "advance" 10 position, the lever 62 and connected mechanism not only fail to function, but the magnetic pole face segments of the timing sleeve are held in the proper "spark advance" 15 position.

With the timing lever in "retard" position and the cam and lever mechanism acting periodically to oscillate the timing sleeve, as hereinbefore described, a quicker separation 20 of the interrupter contacts is accomplished than would be the case were not the timing sleeve thus periodically oscillated. All of the interrupter devices except the interrupter cam 43 being carried by the timing sleeve, it 25 will be seen that when the peak of the current wave is attained and the armature and timing sleeve are simultaneously moving in opposite directions, the relative movement between cam 43 and interrupter arm plug 42 30 is much greater than would be the case were the armature alone being moved. Consequently, the interrupter contacts are rapidly 35 separated and the desirable quick break in the primary circuit effected. It is common knowledge that a quick break in the primary circuit is highly desirable and has a material effect upon the high tension current created in the secondary circuit.

While I have illustrated but one embodiment 40 of my invention, and have shown my invention as applied to but one form of commercial magneto, it is to be understood that I do not so limit myself but claim all the 45 embodiments of my invention coming within the scope of the appended claims.

What I claim as new and desire to secure by Letters Patent of the United States is:

1. An ignition magneto comprising in combination permanent magnets, pole 50 pieces for said magnets, a sleeve between said pole pieces providing segmental faces for said pole pieces, an armature mounted for rotation within said sleeve, and means operated by the armature adapted periodically to move said sleeve in a direction opposite that of armature rotation.

2. An ignition magneto comprising in combination permanent magnets, pole 60 pieces for said magnets, a sleeve between said pole pieces providing segmental faces for said pole pieces, an armature rotatable within said sleeve, and mechanism driven simultaneously with the armature adapted periodically to move said sleeve in a direction opposite that of armature rotation.

3. An ignition magneto comprising in combination with permanent magnets, pole pieces therefor, a timing sleeve comprising magnetic segments constituting movable faces for said pole pieces, an armature 70 rotatable between said pole pieces, a winding carried by said armature, and means arranged twice during each rotation of the armature to move said sleeve in a direction opposite that of armature rotation, and 75 spring means opposing said movement of said sleeve.

4. An ignition magneto comprising in combination with permanent magnets, pole pieces therefor, a timing sleeve comprising 80 magnetic segments constituting movable faces for said pole pieces, an armature mounted for movement within said sleeve, a ring mounted for movement around said sleeve, a timing lever attached to said ring, 85 a stop on said ring, a stop on said sleeve, spring means acting between said ring and said sleeve tending to hold said stops in engagement one with the other, link and lever mechanism connected with said sleeve, and a 90 cam on the armature shaft arranged periodically to act on said link and lever mechanism to move said sleeve in a direction opposite that of armature rotation in opposition to said spring means to accelerate the separation of armature and pole faces for the 95 purpose set forth.

5. An ignition magneto comprising in combination with permanent magnets, pole pieces therefor, a timing sleeve comprising 100 magnetic segments constituting movable faces for said pole pieces, an armature mounted for movement within said sleeve, a ring mounted for movement around said sleeve, a timing lever attached to said ring, 105 a stop on said ring, a stop on said sleeve, spring means acting between said ring and said sleeve tending to hold said stops in engagement one with the other, link and lever mechanism connected with said sleeve, and a 110 cam on the armature shaft arranged periodically to act on said link and lever mechanism to move said sleeve in a direction opposite that of armature rotation in opposition to said spring means to accelerate the 115 separation of armature and pole faces, said timing lever when in one position holding said link and lever mechanism in operative relation to said cam, and when in another position holding said link and lever mechanism out of operative relation to said cam.

6. A magneto comprising in combination with permanent field magnets and a generating winding, a rotor continuously driven when the magneto is in use, to vary the 125 magnetic flux through said generating winding, shiftable pole faces cooperating with said rotor, and means arranged and adapted periodically to move the said pole faces in a direction opposite that of rotor movement 130

to accelerate the rate of change of flux traversing said winding, together with means arranged to restore said pole faces to normal after they have been so moved in the direction opposite that of rotor movement.

7. A magneto comprising in combination with a magnetic field structure having movable pole faces, a rotor movable between said pole faces, an interrupter comprising a stationary contact, and a relatively movable contact, said contacts carried with the pole faces, a cam fixed with respect to the rotor arranged periodically to cause the separation of the interrupter contacts, and means operated from the rotor arranged periodically to move the pole faces, and with them the interrupter contacts, in a direction opposite that of rotor movement.

8. A magneto comprising in combination with a stator and rotor, an interrupter comprising relatively stationary and movable contacts, a support whereon said contacts are mounted, a cam carried by the rotor for effecting the separation of said contacts, and means operated from the rotor arranged periodically to move said interrupter support in a direction opposite the direction of movement of said cam.

9. A magneto comprising in combination with a magnetic field structure and movable pole faces therefor, a sleeve, an armature and means operated by said armature to move said sleeve in a direction opposite that of armature rotation.

10. A magneto comprising in combination with a magnetic field structure and movable pole faces therefor, a sleeve providing pole faces for said pole pieces, an armature and means operated by said armature to move said sleeve in a direction opposite that of armature rotation.

11. A magneto comprising in combination with a magnetic field structure and movable pole faces, a sleeve, an armature, means for moving said sleeve in a direction opposite that of armature rotation and means for restoring said sleeve to normal position after it has been so moved.

12. A magneto comprising in combination with a magnetic field structure and movable pole faces, a sleeve providing pole faces for said pole pieces, an armature, means for moving said sleeve in a direction opposite that of armature rotation and spring means for restoring said sleeve to normal position after it has been so moved.

13. A magneto comprising in combination with a magnetic field structure and movable pole faces, a sleeve providing pole faces for said pole pieces, an armature mounted in said sleeve, means operated by said armature to move said sleeve in a direction opposite that of armature rotation and spring means for restoring said sleeve to normal position after said first movement thereof.

14. A magneto comprising in combination with a magnetic field structure and movable pole faces, a sleeve, an armature, means for moving said sleeve in a direction opposite

site that of armature rotation and means opposing said movement of said sleeve.

15. An ignition magneto comprising in combination permanent magnets, pole pieces therefor, a sleeve providing pole faces for said pole pieces, an armature, means operated by said armature to move said sleeve in a direction opposite that of armature rotation and spring means opposing said movement.

16. A magneto comprising in combination with a magnetic field structure and movable pole faces therefor, a rotor, an interrupter comprising contacts, means for moving said pole faces and said contacts in a direction opposite that of rotor rotation and spring means opposing said movement.

17. A magneto comprising in combination with a magnetic field structure, and movable pole faces therefor, a rotor, an interrupter comprising contacts, means for moving said pole faces and said contacts in a direction opposite that of rotor rotation and means for restoring said pole faces and said contacts to normal position after said movement thereof.

18. A magneto comprising in combination with a magnetic field structure and movable pole faces therefor, a rotor, an interrupter comprising contacts, means for moving said pole faces and said contacts simultaneously in a direction opposite that of rotor rotation and spring means for restoring said pole faces and said contacts to their normal position.

19. A magneto comprising in combination with a stator, a rotor, of an interrupter comprising contacts, supporting means for said contacts, a cam on said rotor for separating said contacts, means operating by said rotor for moving said contacts in a direction opposite that of cam rotation and spring means opposing said movement.

20. A magneto comprising in combination with a magnetic field structure, a sleeve, an armature, a lever connected to said sleeve and a cam on the armature shaft arranged to engage said lever to move said sleeve in a direction opposite that of armature rotation.

21. A magneto comprising in combination with a magnetic field structure, a sleeve, an armature, a lever connected to said sleeve and a cam on the armature shaft for moving said lever to cause rotation of said sleeve.

22. A magneto comprising in combination with a magnetic field structure, a sleeve, an armature, a lever connected to said sleeve, a cam on the armature shaft for moving said lever and yielding means opposing said movement.

23. A magneto comprising in combination with a magnetic field structure, a sleeve, an armature, a lever connected to said sleeve, a cam on the armature shaft for moving said lever, and means for restoring said lever to its normal position.

24. An ignition magneto comprising in combination field magnets, a sleeve, an armature, a lever connected to said sleeve, a cam on the armature shaft for moving said lever to rotate said sleeve and spring means to restore said sleeve to its normal position.

25. An ignition magneto comprising in combination field magnets, a sleeve, an armature, a ring on said sleeve, a timing lever on said ring, lever mechanism connected to said sleeve, a cam on the armature shaft ar-

ranged normally to engage said lever and means operated by said timing lever to hold said lever mechanism in inoperative or operative position.

In witness whereof, I hereunto subscribe my name this 3rd day of April, 1919.

JOHN ROY STARK.
